PAPER STRIP CUTTER AND GLUING APPARATUS

Robert S. Hosmer and Frazier O. Hosmer,
Birmingham, Ala.

Application January 10, 1948, Serial No. 1,565

10 Claims. (Cl. 216—21)

1

Our invention relates to apparatus for cutting a strip of paper from a sheet and gluing the same to an envelope, pay check, card, or the like, and has for an object the provision of apparatus of the character designated embodying means operable to cut successive strips of paper from a sheet, glue each strip to an envelope, and eject the envelope after the strip is glued thereto.

A further object is to provide apparatus of the character designated in which a rotatable relatively wide roller is mounted on a suitable carriage for reciprocation closely adjacent a stationary cutter, whereby a sheet placed over the cutter has a strip sheared therefrom by the coaction of the moving roller and stationary cutter, together with means responsive to reciprocation of the carriage to feed the sheet inwardly once during each cycle of reciprocation, the feed means being so regulated that a strip of the correct width is placed in position to be sheared by the roller.

Another object of our invention is to provide an applicator for placing liquid or semi-liquid adhesive on the second envelope from the top of a stack of envelopes during the ejection or non-cutting stroke of the carriage, together with means to raise the adhesive applicator out of contact with the envelope and strip during the cutting stroke of the carriage, thus assuring that adhesive is placed only on the surface of the envelope which is to receive the strip.

Another object is to mount the strip shearing roller above a stack of envelopes biased upwardly by means of a spring, whereby the roller simultaneously cuts and presses the strip into contact with the surface of the envelope to which adhesive has previously been applied by the applicator, together with an ejector for removing the uppermost envelope from the stack after the strip is pressed into contact thereon and on the return or non-cutting stroke of the carriage.

Further objects of our invention are to provide apparatus of the character described in which the roller and cooperating stationary cutters are free of sharp surfaces or edges capable of injuring an operator's hand; in which the adhesive applicator is automatically inoperative during that portion of the operating cycle when adhesive is not being applied; to provide mechanism whereby a strip may, by a simple manipulation of the controls, be cut from the sheet but not glued to an envelope, together with means to eject such a strip from the apparatus; and to provide apparatus which may be used selectively as a strip cutter, an adhesive applicator,

2

a sheet perforator, or a combination of the above.

Apparatus embodying the features of our invention is illustrated in the accompanying drawing forming a part of this application in which—

- 5 Fig. 1 is a side elevational view of our improved apparatus partly broken away and in section, and showing a stack of envelopes in place therein with the uppermost envelope of the stack in the process of being ejected;
- 10 Fig. 2 is a detail sectional view taken generally along the line II—II of Fig. 1;
- Fig. 3 is a plan view of the discharge end of the apparatus with certain parts broken away for the sake of clarity;
- 15 Fig. 4 is a detail sectional view of the adhesive tank and applicator roller;
- Fig. 5 is a detail sectional view taken along the line V—V of Fig. 1, drawn to an enlarged scale, and illustrating the envelope ejecting mechanism;
- 20 Fig. 6 is a detail sectional view taken along line VI—VI of Fig. 2 and showing the ejector for removing the rejected strip from the apparatus;
- 25 Fig. 7 is a detail sectional view illustrating a modified form of cutting roller and stationary cutters;
- Fig. 8 is a diagrammatic view on an enlarged scale illustrating the method of cutting and pressing the strip into contact with the surface of the envelope.
- 30 Referring now to the drawing for a better understanding of our invention, our improved apparatus comprises a frame 10 which may be of metal bent to form an elongated box open at the rear end 11. At the rear end 11 of the frame, on the top thereof, we mount a bracket 12, and adjacent the discharge end 13 we mount a bracket 14.
- 35 Secured to the brackets 12 and 14 are a pair of upper and lower rods 16 and 17. Mounted to reciprocate on the rods between the brackets 12 and 14 is a carriage indicated generally by the numeral 18 and provided with openings 19 and 21 through which pass the rods 16 and 17, respectively. Rotatably mounted on the lower part of the carriage 18 in any suitable manner as by means of a stud 22 is a relatively wide roller 23. As shown more clearly in Fig. 2 the roller 23 projects slightly below the top edges of a slot 24 formed in the top 26 of the box-like frame 10. The roller 23 is thus disposed to contact with the edges 24a and 24b of the slot 24 to shear a sheet of paper or other material as
- 45
- 50
- 55

the carriage reciprocates on the rods 16 and 17, as will be explained.

The carriage is provided with a third opening 27 in which is slidably disposed a short rod 28. The rod 28 is provided with stop pins 29 and 31 on either side of the carriage thereby to limit its axial movement in the opening 27. The ends 32 and 33 of a flexible cable 34 are secured to the ends of the rod 28, and are threaded over pulleys 36 and 37 rotatably mounted in suitable brackets 38 and 39 carried respectively by the end brackets 12 and 14. Mounted in a bearing 41 at the top of the end bracket 12 is the shaft 42 of a drum 43 about which the cable is wrapped. The drum is provided with a crank 44 by means of which the same may be rotated. It will be apparent that when drum 43 is rotated, carriage 18 reciprocates back and forth, the pins 29 and 31 acting as stops to transmit the motion of the cable through rod 28 to the carriage, and allowing a slight lost motion between the rod 28 and carriage.

The box-like frame 10 provides a compartment 46 beneath the slot 24 and roller 23 for the reception of a stack of individual envelopes E. Disposed within the opening 46 is an elongated plate 47, movable vertically within the compartment 46, on top of which is placed the stack of envelopes. Beneath the plate 47 is an arm 48 mounted on a cross shaft 49, journaled in suitable bearings 51 and 52 carried by the frame 10. One end of the rod 49 projects from the frame 10 and carries a handle 53. A spring 54 is secured at one end to the handle 53 and at the other end to a pin 56 projecting from the side of the frame 10. Adjacent the discharge end 13 of the frame is a wall 57 for the compartment forming a stop for the end of the stack of envelopes. The upper end of the wall terminates below the top 26 to permit an envelope to slide off the top of the stack. The stack of envelopes resting on the plate 47 is biased upwardly by the spring 54 thereby to position the uppermost envelope E of the stack in contact with the lower side of the top 26 of the frame 10, and to position it immediately below the slot 24 and roller 23.

On the side of the carriage adjacent the end bracket 12 is a lug 58. Pivotally mounted as at 59 to the lug 58 is the upper end of a small tank or container 61 for holding a supply 62 of liquid or semi-liquid adhesive. See Fig. 4. The bottom 63 of the tank slopes toward the lower inclined wall 64 thereof and in the resultant low corner of the tank we provide an elongated opening 66. The sidewalls of the tank 61 extend below the opening 66 as indicated at 67 to provide means for rotatably supporting a roller 68. The sidewalls 67 are provided with slightly elongated openings 69 for receiving the shaft 71 of the roller 68. By reference to Fig. 4, it will be seen that when shaft 71 is in the upper part of slot 69, the opening 66 is uncovered so that adhesive is free to flow onto the roller from the opening. When the shaft 71 occupies the lower part of the slot, as when the roller 68 moves to the dotted line position shown in Fig. 4, the surface of the roller closes the opening 66 and no adhesive can flow from the tank.

As shown in Figs. 1 and 4, the side 64 of the tank carries a lug 72 having an elongated opening 73 therein. Fitting within the opening 73 is a pin 74 projecting outwardly from the rod 28. It will be apparent that when the carriage 18 commences to move to the left as viewed in Fig. 1, the

rod 28 moves to the left until the pin 74 carried thereby strikes the end of the carriage. This action causes pin 74 to pivot the entire adhesive tank 61 and roller 68 downwardly about the pivot point 59, causing the roller 68 to contact the surface of the second envelope from the top of the stack, uncovering the opening 66, and applying to the second envelope a thin layer of adhesive of a width substantially equal to the width of the opening 24. Upon reverse movement of the carriage, the roller 68 is lifted upwardly out of contact with the envelope and moves downwardly by gravity in the slotted openings 69, thereby closing the opening 66 and stopping the flow of adhesive from the tank.

Our improved mechanism for feeding the sheets of material to be cut into strips and placed on the envelopes will now be described. Mounted at one side of the frame 10 and extending parallel with the slot 24 we provide a pair of sheet feeding rollers 76 and 77. The shaft of upper roller 76 is mounted in suitable bearings 78 and 79. The shaft of lower roller 77 is mounted at each end on arms 81 and 82, the lower end of the arms being secured to a shaft 83 journaled in suitable bearings 84 and 86, mounted on the side of the frame 10. The shaft 83, and consequently arms 81 and 82 and the lower roller 77, are free to pivot about the bearings 84 and 86, and a spring 87, see Fig. 2, serves to hold the roller 77 in contact with the roller 76. The arm 81 is provided with a handle 88 by means of which the lower roller may be manually separated from the upper roller 76 thereby to permit a sheet of material to be inserted between the rollers when desired.

The shaft of the upper roller 76 is provided with a worm gear 89 adjacent the discharge end 13 of the apparatus. Meshing with the gear 89 is a second worm gear 91 fast on a vertically disposed shaft 92 journaled in suitable brackets 93 and 94 which may be formed integrally with the end bracket 14. The upper end of shaft 92 carries a pinion 96. When the pinion 96 is rotated, the upper roller 76 rotates, and a sheet of paper disposed between the rollers 76 and 77 is fed inwardly over the slot 24 in the top 26 of the frame 10. A holding pawl 97, biased into contact with the pinion by means of a spring 98, may be provided to prevent counter-rotation of the pinion 96 and its shaft 92.

Pivottally mounted as at 99 on top of the carriage 18 is a rack 101. The rack is so positioned with respect to the pinion 96 that it engages and rotates the pinion when the carriage moves from its extreme left hand position toward the right. A spring 102 pulls the rack 101 outwardly into the position to mesh with the pinion 96, and into contact with a limit stop 103.

After the envelope has had the strip of paper glued thereto, we provide means for ejecting the envelope from the top of the stack. As shown more clearly in Figs. 1 and 5, the carriage 18 is provided with an offset arm 104 disposed over the opening 24. The arm 104 carries depending lugs 106 and 107. Between the lugs is a pin 108 on which is pivotally mounted an ejector plate 109. The plate is of a width to fit within the slot 24 and is provided at its upper end with an angularly disposed portion 111. Mounted between the brackets 106 and 107 adjacent the angular portion 111 is a cross pin 112. With the carriage moving to the left as viewed in Fig. 1, the lower end of the plate 109 engages behind the edge of the uppermost envelope E of the stack and slides the same to the left over the top of wall 57, re-

moving it from the apparatus. The extension 111 strikes pin 112 to prevent counterclockwise rotation of the plate as viewed in Fig. 1. The ejector is free to rotate clockwise when the carriage is moving to the right as viewed in Fig. 1, thereby sliding over the uppermost envelope of the stack on the strip cutting stroke of the carriage.

During the cutting of sheets into strips it is sometimes desirable to cut a strip and not glue the same to an envelope, and to eject such a strip from the apparatus. As shown in Figs. 2 and 6, we mount on the side of the carriage opposite the slot 24 an ejector 113. The ejector is mounted for pivotal movement on a pin 114, and a stop pin 116 is disposed to engage an extension 117 on the ejector, thereby to limit its clockwise rotation as viewed in Fig. 6. The lower part of the ejector projects under the side of the carriage 18 as shown at 118, Fig. 2, thereby to provide a relatively wide foot for engaging the end of a rejected strip and ejecting the same from the machine, as will later be explained.

Referring now particularly to Fig. 7, we show a modified form of cutting roller and stationary cutter elements therefor. As shown, the roller 119 is provided adjacent each end with concave depressions 121. At the ends the roller 119 has secured thereto by screws 122 removable annular disc cutters 123, the peripheries of which coact with a pair of stationary cutter elements 124 to shear the sheet. The roller may be mounted for rotation on the carriage 18 by a stud 126, in the same way as roller 23 is mounted. We have found that the depressions 121 aid the roller in shearing certain types of paper by providing a small relief for the paper at the point of shear.

It will be apparent that a sheet of paper placed over the cutters 124 is sheared by the passage thereover of the discs 123 carried by roller 119. The central portion 119a of the roller presses the strip so cut into contact with the envelope beneath the cutters 124 and the opening therebetween, in the same way as does the roller 23.

From the foregoing, the operation of our improved strip cutting and gluing apparatus may now be readily explained and understood. To insert a stack of envelopes, the handle 53 is pulled downwardly, releasing the arm 48 and permitting the plate 47 to move downwardly in the compartment 46. The stack of envelopes is slid into the compartment with the ends of the envelopes contacting the wall 57. The handle is released, whereupon spring 54 presses the stack upwardly into contact with the underside of the top 26. The sheet of paper to be cut into strips and pasted on the envelope is inserted between the rollers 76 and 77 by pulling downwardly on the handle 88 to separate the rollers. With the carriage to the right as viewed in Fig. 1, handle 44 is rotated to move the carriage 18 to the extreme left position as viewed in Fig. 1, a supply of adhesive being previously placed in the tank 61. Adhesive is supplied to the second lowermost envelope while the uppermost one is ejected as a blank. The handle 44 is now rotated in a direction to pull the carriage to the right. The rack 101 engages pinion 96, rotating the shaft 92 and roller 76, thereby feeding the sheet of material inwardly to lie over the slot 24. During this movement the adhesive roller 68 is lifted upwardly and closes the opening 66. The diameter of the rollers 76 and 77, the ratio between the gears 89—91, pinion 96 and its rack 101 are such that a strip substantially the width of the slot 24 is fed inwardly each time the roller 76 rotates. Continued right-

ward movement of the carriage causes the roller 23 to engage the top of the sheet, and, in cooperation with the edge 24a of the opening 24 shears the strip as illustrated in Fig. 8. The strip S, simultaneously with the cutting thereof, is pressed into contact with the upper surface of the uppermost envelope E of the stack, and is glued thereto. As soon as the carriage reaches the end of its traverse toward the right, handle 44 is operated in the opposite direction, moving the carriage again to the left. This motion causes the ejector plate 109 to engage behind the uppermost envelope and propel the same to the left. Simultaneously, the roller 68 is pressed into contact with the next subjacent envelope E of the stack, the shaft 71 thereof shifting in the slot 69 thereby to uncover the passage 66 permitting a flow of adhesive onto the roll 68, and depositing a film of adhesive on the subjacent envelope. The pivoted rack slips over the teeth of the pinion 96, the holding pawl 97 assuring no counter rotation of the shaft 92 and hence the roller 76. At the end of the leftward movement, the handle 44 is rotated oppositely, thus shifting the rod 28 in the opening 27, simultaneously raising the tank 61 and roller 68, gravity causing the roller 68 to move downwardly in slot 69 to again seal the opening 66 for the duration of the movement to the right. The ejector plate 109 slides over the top of the envelopes whenever the carriage is moved to the right, since the same is free to pivot clockwise on the pin 108.

From the foregoing, it will be apparent that we have devised an improved strip cutting and gluing machine which is fully effective for its intended purpose. The machine is particularly adapted for use in separating individual columns of a composite pay record sheet and pasting the strips on a pay record, such for instance as a pay envelope. A pay roll sheet of this type is shown, described and claimed in the copending application of Frazier O. Hosmer, Serial No. 647,977, filed February 15, 1946, now Patent No. 2,440,337. While especially adapted for use in connection with the pay roll sheets above identified, it will be apparent that our machine may be used for various purposes. For instance, it may be used as a paper cutter alone by removing the spring 87 and permitting the feed roller 71 to drop downwardly and by omitting the adhesive from the tank 61. Likewise the roller 23 may be removed and the gluing feature used to place a strip of glue or adhesive on any desired sheet. Likewise, by substituting a spiked roller for the roller 23 and omitting the supply of adhesive from the tank 61, our machine may serve effectively as a perforator, the sheets to be perforated being placed either on the plate 47 for single line perforation, or fed through the rollers 76 and 77 for multiple line perforation.

As before stated, during the process of cutting strips from a sheet it is sometimes desired to cut one of the strips and eject the same from the machine without gluing it on an envelope. Such an operation is accomplished by our apparatus in the following manner. The crank 44 is operated in a direction to pull the carriage to the right, Fig. 1, until the rack 101 engages and rotates the pinion 96, and feed roller 76. Instead of continuing the rightward movement of the carriage, the handle 44 is now rotated oppositely thereby causing the carriage to move back to the left. Upon rotating the handle in a direction to move the carriage again to the right, the rack 75 101 engages the pinion 96, rotating the feed roll

18 a second time, thus feeding the strip over the edge 24b of the slot 24. Upon continued movement to the right, the roller cuts and glues one strip onto an envelope and at the same time cuts and leaves a strip overhanging to the right of the slot 24 as viewed in Fig. 2. Upon leftward movement of the carriage the overhanging strip is ejected by the ejector 113 carried by the carriage 18 as already described.

While we have shown the stationary cutters as being the sides of the opening 24, it will be apparent that removable cutter elements similar to the elements 124 may be positioned in suitable manner on the top 26 of the frame adjacent slot 24 to coact with roller 23 in shearing the strips. It will likewise be apparent that instead of supplying adhesive from the tank 61, we may fill the same with a suitable solvent for a dried glue which has been previously applied to the envelopes. If desired the sheet from which the strips are being cut may be coated with dried adhesive and the solvent applied from tank 61 to the envelope.

From the foregoing it will be apparent that we have devised an improved apparatus for cutting and gluing a strip to an envelope or the like embodying means to automatically cut and glue the strip to an envelope and eject the envelope upon completion of the strip securing operation. The roller 23, being relatively wide and free of sharp edges, together with the flat cutters formed by the edge of the slot 24 or the separate cutters 124 make for safety in operation since these parts are not sufficiently sharp to injure an operator's hand. While we have shown and described the strips as being applied to envelopes, it is apparent that our machine is equally suited to cut and apply the same to such records as checks, cards, ledger sheets, etc.

While we have shown our invention in but two forms, it will be obvious to those skilled in the art that it is not so limited, but is susceptible of various other changes and modifications, without departing from the spirit thereof, and we desire, therefore, that only such limitations shall be placed thereupon as are specifically set forth in the appended claims.

What we claim is:

1. In apparatus for cutting a strip from a sheet of material and pressing the strip into contact with an envelope, a carriage, a cutting roller mounted on the carriage, a stationary cutter having an edge cooperating with the roller to shear the sheet, means to position the sheet over the edge of the cutter, means to place an envelope beneath the roller and disposed to hold the envelope in position for the roller to press the strip into contact therewith, and means to move the carriage whereby the roller simultaneously shears the strip and presses the same against the envelope.

2. In apparatus for cutting a strip of paper from a sheet and pressing the strip into contact with an envelope and the like, a carriage, a cutting roller mounted on the carriage, a stationary cutter having an edge disposed to cooperate with the roller to shear the strip from the sheet, means to position the sheet over the edge of the cutter, a holder for a stack of envelopes beneath the roller, means to bias the stack of envelopes toward the roller, and means to move the carriage and roller over the sheet of material whereby the roller simultaneously shears the strip and presses it against the uppermost envelope of the stack.

3. Apparatus as defined in claim 2 in which

the means to position the sheet over the cutter comprises a pair of feed rollers disposed alongside the cutter and between which the sheet is received, and means operable responsive to movement of the carriage to rotate at least one of said rollers thereby to feed the sheet over the cutter.

4. Apparatus as defined in claim 3 in which the means to rotate the feed rollers comprises a pivotally mounted rack carried by the carriage, a pinion disposed in the path of the rack, and gears to transmit rotary motion of the pinion to one of the feed rollers.

5. In apparatus for cutting a strip from a sheet of material and gluing the same to an envelope, a reciprocable carriage, a roller mounted on the carriage, a stationary cutter having an edge disposed to cooperate with a side of the roller to shear the sheet when the carriage moves in one direction, means to position the sheet over the cutter, a holder for a stack of envelopes beneath the roller and stationary cutter, means to bias the stack of envelopes upwardly with the uppermost envelope positioned to have the strip pressed into contact therewith by the roller, an adhesive applicator carried by the carriage and adapted to place adhesive on the subjacent envelope lying immediately beneath the uppermost envelope when the carriage moves in the opposite direction, and means carried by the carriage to eject the uppermost envelope of the stack when the carriage moves in a direction to place adhesive on said subjacent envelope.

6. Apparatus as defined in claim 5 in which the adhesive applicator comprises a tank pivotally mounted to the carriage, an adhesive applying roller mounted for rotation beneath the tank, there being an opening in the bottom of the tank through which adhesive therein flows onto the roller, and a link connection between the carriage and the tank to raise the tank and roller out of contact with the sheet when the carriage moves in a direction to cut the strip.

7. In apparatus of the character described, a reciprocable carriage, a cutting roller mounted for rotation on the carriage, a stationary cutter element disposed beneath the roller to cooperate therewith and shear a sheet of material, a holder for receiving a stack of envelopes disposed beneath the roller and stationary cutter, means to bias the stack of envelopes toward the roller, a pivotally mounted adhesive applicator carried by the carriage and disposed when the carriage is moving in one direction to contact and place adhesive on an envelope in the stack and when the carriage is moving in the other direction to be raised out of contact with the envelopes in the stack, a pair of sheet feeding rollers disposed alongside the cutting roller, means to reciprocate the carriage, and means responsive to reciprocation of the carriage to rotate one of the sheet feeding rollers, thereby to position the sheet over the cutter elements in position for the cutting roller to shear the same.

8. In apparatus of the character described, a reciprocable carriage, a roller mounted on the carriage, stationary cutters disposed at each end of the roller and cooperating therewith to shear a pair of strips from a sheet, means to reciprocate the carriage, sheet feeding mechanism constructed and arranged to position the sheet over the cutters responsive to movement of the carriage in one direction, means to place an envelope beneath the roller in position for one of said strips to be pressed into contact therewith by the

roller, an ejector mechanism on the carriage disposed to eject the envelope onto which said strip is pressed when the carriage moves in an opposite direction, and another ejector on the carriage operable to eject the other strip when the carriage moves in said opposite direction.

9. In apparatus for separating a sheet of material into strips and gluing the strips onto envelopes and the like, a reciprocable carriage, a roller mounted on the carriage, a stationary cutter disposed to cooperate with the roller to shear strips from the sheet when the carriage moves in one direction, means to feed the sheet over the cutter, a shiftable pin in the carriage, stops on the pin to limit the shifting movement thereof, a cable having its ends secured to opposite ends of the shiftable pin, a friction drum about which the cable is wound, means to rotate the drum in opposite directions thereby to shift the pin and reciprocate the carriage, an adhesive applicator pivotally mounted on the carriage, a connection between the applicator and pin whereby the applicator is lowered when the pin shifts in one direction and is raised when the pin shifts in the opposite direction, a stack of envelopes beneath the roller and cutter with the uppermost envelope of the stack disposed to have the strip pressed thereagainst by the roller when the carriage moves in a direction to lift the adhesive applicator, and ejector mechanism for removing the envelope carrying strip when the carriage moves in directions to lower the adhesive applicator onto the next subjacent envelope of the stack.

10. In apparatus of the character described, a reciprocable carriage, a roller mounted on the carriage, an elongated stationary cutter with which the roller cooperates to shear strips from a sheet of material, a pair of feed rollers dis-

posed alongside the stationary cutter and adapted to receive between them the sheet of material to be cut into strips, a pinion at one end of the feed rollers, a rack on the carriage disposed to engage and rotate the pinion when the carriage moves toward the opposite ends of the feed rollers, gears operable to transmit rotary motion of the pinion to one of the feed rollers thereby to feed the sheet inwardly over the stationary cutter, means to support a stack of envelopes beneath the stationary cutter embodying an upwardly biased plate on which the stack rests, a tank for a supply of adhesive pivotally mounted on the carriage, a roller beneath the tank disposed to receive adhesive therefrom when the tank is in lowered position and place the same on an envelope of the stack, drive means for reciprocating the carriage, a lost motion connection between the drive means and carriage, and means operable through the lost motion connection to raise the tank and roller carried thereby out of contact with the envelopes when the carriage moves toward the said opposite ends of the feed rollers.
